FIREPLACE DAMPER CONSTRUCTION

Henry A. Benjamin, Oakland, Calif.

Application May 23, 1938, Serial No. 209,423

5 Claims. (Cl. 126—288)

My invention is concerned with the provision of an improved damper construction for fireplaces.

It is the object of the invention to provide improved damper means for fireplaces, which is of a simple, inexpensive construction; which can be installed easily, and which provides for ready adjustment of the damper lid to any desired position.

10 Other objects will be apparent from the following description of a preferred embodiment of the invention as illustrated in the accompanying drawing, in which:

Figure 1 is a vertical section through a fireplace 15 having the damper means of my invention installed therein, the view being taken in the plane of the line 1—1 in Figure 2.

Figure 2 is a horizontal sectional view of one end of the fireplace taken as indicated by the line 2—2 in Figure 1.

20 Figure 3 is a fragmentary sectional view taken as indicated by the line 3—3 in Figure 2.

Referring to Figures 1 and 2, a fireplace 10 of a conventional construction is shown, with the 25 brick or stone walls which define the fireplace and the chimney 11 shown schematically. As usual, a lintel 12 is provided across the front of the fireplace to support the front wall 13 and having its ends supported on side walls 14 of the fireplace. The lintel 12 has its upwardly extending flange 16 spaced from rear wall 17 to provide the throat between the fireplace and its chimney.

In accordance with my invention, the lintel 30 itself forms a part of the damper construction, and imperforate end brackets 18 are associated therewith to form the frame of the damper. Similar end brackets 18 (Figs. 1-3) are provided which may be secured to the lintel 12 in spaced 35 apart relation to be supported on respective side walls 14 and form smooth upward continuations thereof. Each bracket 18 is provided with base flange 19, vertical imperforate wall 20, and lintel engaging flange 21 which may be riveted or otherwise 40 secured to the lintel as at 22. Base flange 19 may be embedded in the adjacent wall and is preferably provided with an extension 23 (Figs. 2 and 3) which is also embedded in the adjacent wall. As seen in Figs. 1 and 2 the rear portion 45 of each bracket 18 may extend into and be embedded in wall 17, if desired.

From the above description, it will be seen that the lintel and the end brackets form a frame 50 which is built into the walls of the fireplace and

with rear wall 17 define the throat opening thereof, which is opened and closed by the damper 26.

Damper 26 is mounted for pivotal movement on the lintel and preferably has a freely detachable connection therewith. As seen in Figures 5 1 and 2, damper 26 comprises an arcuate plate, which is formed to correspond to the shape of the upper edges of brackets 18, and has a pair of similar spaced pivot lugs 27 received in respective slots 28 formed in the upper edge of lintel 10 flange 16 adjacent respective upright damper engaging projections 29 thereof. It is seen, therefore, that damper 26 is mounted for pivotal movement at its lower and forward edge, the mounting preventing endwise movement thereof while 15 providing for free lifting of the damper when its removal is desired.

The damper can be adjusted to any desired position from the closed dotted line position thereof shown in Figure 1 in which its rear edge 20 rests on the top of rear wall 17, by adjusting means of a construction to enable easy operation while providing a minimum exposure of the operating parts to the direct action of the fire and smoke. The adjusting means comprises nut 31 (Figs. 1 and 2) disposed in opening 32 in damper 26, and having trunnions 33 pivotally secured on the damper by bearing brackets 34. Nut 31 is threadedly engaged by screw 36 having a universal connection 37 at its upper end with adjusting shaft 38 journaled in tube 39, which is built into front wall 13. Suitable washers 40 are provided at each end of tube 39, and operating handle 41 is secured on the projecting end of adjusting shaft 38. By turning handle 41, the 35 damper can be moved to any desired position, and will be positively maintained therein by the locking action of the nut and screw.

From the above description, it will be seen that the improved damper construction of my invention 40 can be installed with a minimum of work, and that the damper itself can be removed easily for subsequent inspection, cleaning, or repair of the fireplace. In addition, the adjustment is positive and not subject to clogging or deterioration in use.

While I have shown and described a preferred embodiment of the invention, it is to be understood that the invention may be embodied in other forms, and that its scope is to be limited 50 only by the scope of the claims appended hereto.

I, therefore, claim as my invention:

1. In a damper construction for fireplaces, a lintel having a horizontal wall supporting flange and a flange projecting upwardly therefrom, a 55

pair of end brackets associated with said lintel having imperforate walls to provide portions of the fireplace side walls, a damper having a freely detachable pivotal connection with said upwardly projecting lintel flange, and adjusting means extending from the upper side of said damper including an adjusting shaft for journalling in the front wall of the fireplace.

2. In a damper construction for fireplaces, a lintel having a horizontal wall supporting flange and a flange projecting upwardly therefrom, a pair of end brackets associated with said lintel having imperforate walls to provide portions of the fireplace side walls, a damper having a freely detachable pivotal connection with said upwardly projecting lintel flange, a nut pivotally connected to said damper, a screw associated with said nut, an adjusting shaft for mounting in the front wall of the fireplace, and a universal connection between said screw and said shaft.

3. In a damper construction for fireplaces; a

lintel; a damper pivotally mounted on said lintel, and adjusting means associated with damper for effecting movement thereof, said adjusting means including a shaft for journalling in the wall of said fireplace above said damper and an adjusting element connected to said damper and driven by said shaft.

4. In a damper construction for fireplaces; a lintel; a damper pivotally mounted on said lintel, a nut connected to said damper, a screw associated with said nut, an adjusting shaft located above said damper, and a universal connection between said screw and said shaft.

5. In a damper construction for fireplaces; a lintel; a damper mounted on said lintel by a freely detachable pivotal connection, a nut connected to said damper, a screw associated with said nut, an adjusting shaft located, above said damper, and a universal connection between said screw and said shaft.

20
HENRY A. BENJAMIN.
